[57] **CLAIM**

The ornamental design for a cradle for a remote control, as shown and described.

DESCRIPTION

FIG. 1 is a perspective view of a cradle for a remote control showing my new design, the broken lines being illustrative of environmental structure and forming no part of the claimed design;

FIG. 2 is an additional perspective view of the cradle for a remote control shown in FIG. 1;

FIG. 3 is a front view thereof;

FIG. 4 is a right side view, the left side being a mirror image thereof;

FIG. 5 is a rear view thereof;

FIG. 6 is a top view thereof; and,

FIG. 7 is a bottom view thereof.
